UNITED STATES PATENT OFFICE.

OLNEY B. MONOSMITH, OF LORAIN, OHIO.

CARBURETER.

1,194,055.

Specification of Letters Patent. Patented Aug. 8, 1916.

Application filed August 17, 1914. Serial No. 857,058.

To all whom it may concern:

Be it known that I, OLNEY B. MONOSMITH, a citizen of the United States, residing at Lorain, in the county of Lorain and State of Ohio, have invented certain new and useful Improvements in Carbureters, of which the following is a specification.

This invention relates to carbureters for internal-combustion engines, and is an improvement in both structure and efficiency over the carbureter disclosed in my former application filed Feb. 9, 1914, and having Serial No. 817,404.

The principal object of the present invention is to provide a carbureter adapted to operate economically at varying speeds of the engine in the same general way as my said other carbureter; but is so constructed that the removable parts may be more conveniently interchanged to make the carbureter suitable for different engines, and the adjustments for regulating the flow from the auxiliary carbureting chamber made by simply turning an easily accessible outside valve.

In order that the invention may be clearly understood, the same will be hereinafter fully described in connection with the accompanying drawings which illustrate a preferred embodiment thereof, and the novel features of the invention will be distinctly pointed out in the appended claims.

In the drawings like characters of reference indicate corresponding parts.

Figure 1 is a sectional elevation of a carbureter illustrating my invention, Fig. 2 is a sectional view taken on line 2--2 of Fig. 1, Fig. 3 is a plan section taken on line 3--3 of Fig. 1, and Fig. 4 is a perspective view of the spray plate.

Referring to the drawings, 1 represents a vertical air passage, which is cylindrical in cross section, and extending at a right angle therefrom is its inlet end indicated by 2.

A butterfly valve 3 is adapted to control the air inlet. The lower part of the air passage 1 is bored slightly larger, as shown at 4, to receive a V shaped spray plate 5 and provide a shoulder 6 against which its upper edge abuts. The spray plate 5 is admitted at the lower open end of the air passage, which is threaded at 7 for receiving a dished cap 8. This cap is provided with a central projecting boss 9 for engaging the bottom of the spray plate to hold it in place by forcing it against said shoulder 6. The cap is

preferably provided with a nut portion 10 for the accommodation of a wrench. Said spray plate 5 is preferably formed from a single strip of metal of a width equal to the bore 4, and consists of a pair of diverging or inclined sides 11 joined together by the bottom 12. The edges of the sides 11 are curved to conform to the bore 4, and it will be noted that the spray plate entirely separates the lower portion of the air passage from its upper part. The sides 11 of the spray plate are provided with perforations 13, and these perforations are preferably evenly staggered and made tapering with their larger areas at the inner surfaces of the sides to produce a Venturi action as the air passes therethrough.

The outer wall of the air passage 1 is considerably thickened at 14 and just above the top of the spray plate this wall is provided with a horizontal main feed opening 15 leading to a vertical opening or well 16 in said thickened wall. Communication from the float chamber 17, supported on the side of said thickened wall, to the lower end of the vertical opening 16 is established by means of a recess 18, which extends from the lower part of the float chamber. In order to provide convenient means for regulating the flow of gasoline from the float chamber to the vertical opening 16, the lower end of the thickened wall 14 is bored at 19 and threaded at 20 for receiving a removable plug nozzle 21. A lateral opening 22 in the plug nozzle permits the gasoline to flow from the recess 18 of the float chamber up through its hollow center 23 and then out of its conical shaped outlet 24 into the vertical opening 16. The purpose of making the outlet 24 conical is to provide a sharp edge to reduce the friction of the flow of the gasoline through the outlet, and also to provide an uninterrupted flow. The joint under the head 25 of the plug nozzle may be made tight against leakage by a suitable washer 26. By employing plug nozzles having different sized outlets, the flow of the gasoline into the vertical opening 16 may be delicately regulated.

The upper portion of the vertical opening 16 above the main feed opening 15 is an auxiliary carbureting chamber, and leading therefrom into the air passage 1 is an auxiliary feed opening 27, the outer end of which is enlarged at 28 to form a valve seat 29. The flow from said auxiliary feed opening

is controlled by means of a valve 30, which is slightly smaller in diameter than the enlarged portion of said opening and is adapted to coöperate with the valve seat 29. The 5 valve 30 is operatively mounted in a plug fitting 31, which is screwed into a threaded opening 32, and is provided on its outer end with a cap 33 adapted to serve as a packing box for the valve stem. The valve may be 10 readily adjusted from the outside by means of the handle 34. A throttle valve 35 is arranged in the outlet of the air passage, and is so positioned that when closed, its edge partially closes the auxiliary feed opening 15 27 for a purpose hereinafter explained.

It will be noted that the spray plate 5, and the plug nozzle 21 are readily removable, while the valve 30 may be easily adjusted. The main purpose of making these parts in 20 this way being to construct a standard carbureter, wherein a spray plate having different numbers of perforations may be used, or the plug nozzle exchanged for another provided with a different sized outlet, or the 25 valve adjusted to give a different sized auxiliary feed opening. It will be appreciated that this is necessary for obtaining the best results for different types and H. P. of engines.

30 Now that the construction of the carbureter has been fully disclosed, the operation of the same will be explained: In starting the engine, the butter-fly valve 3 is closed and the throttle valve 35 slightly opened. 35 This causes a vacuum in the air passage, and the gasoline flows from the main feed opening 15 down onto the inner surfaces of the sides of the spray plate 5. The butter-fly valve 3 is then fully opened to admit air, 40 which passes through the tapering perforations 13 of the spray plate, thereby creating a Venturi action which causes the thin film of gasoline upon the inner surfaces of its sides to become mixed with the air, and this 45 uniform rich mixture enters the engine for starting the same.

To run the engine at slow speed, the throttle valve 35 is closed with its edge partially covering the auxiliary feed opening 27 as 50 shown, the butter-fly valve 3 remaining fully open to admit air. This incoming air circulates under the bottom of and around the outside of the spray plate 5 and passes through the perforations 13, then upwardly 55 between the side of the spray plate. A part of this air rushes between the edge of the throttle valve 35 and the auxiliary feed opening 27, while the balance enters the main feed opening 15, thereby substituting 60 an outward flow of air for an inward flow of gasoline. This prevents the gasoline from flowing onto the sides of the spray plate during the operation of the auxiliary carbureting chamber. The circulation of 65 air currents through the main feed opening

15 laps the surface of the gasoline in the lower part of the vertical opening 16 and mixes therewith. This mixture flows upwardly through the upper part of the vertical opening 16, and then inwardly through the auxiliary feed opening 27 into the air passage for running the engine at very slow speed. To increase the speed of the engine from its slowest speed is as follows: The 70 operation of the auxiliary carbureting chamber stops as soon as the vacuum in the air passage caused by the action of the spray plate 5 is sufficient to cause the gasoline to flow from the main feed opening 15. The 75 progression of flow of air and gasoline from this point to the highest speed of the engine is controlled by the law of capillary flow.

It will be understood that slight changes in the construction and arrangement of parts may be made within the scope of the 85 claims.

Having fully described my invention what I claim is:

1. In a carbureter, the combination of an air passage, the air passage having a feed opening through its wall, a float chamber connected with the feed opening, a bent-up spray plate consisting of a pair of diverging sides connected by a bottom arranged within the air passage for receiving the flow 90 from the feed opening upon its inner surfaces, and the spray plate being perforated, substantially as described.

2. In a carbureter, the combination of an air passage, the air passage having a feed 100 opening through its wall, a float chamber connected with the feed opening, a bent-up spray plate consisting of a pair of flat diverging sides connected by a bottom arranged within the air passage for receiving the flow 105 from the feed opening upon its inner surfaces, the spray plate being provided with perforations, and the perforations having tapering sides with their larger areas at the inner surfaces of the spray 110 plate, substantially as described.

3. In a carbureter, the combination of a vertical air passage having a side inlet, the air passage having a feed opening through its wall, a float chamber connected with the 115 feed opening, a removable V shaped spray plate arranged within the air passage below said feed opening for receiving the flow from the feed opening upon its inner surfaces, the spray plate being perforated, the 120 air passage having a lower open end for admitting the spray plate, and means for closing said open end of the air passage, substantially as described.

4. In a carbureter, the combination of a 125 vertical air passage having a side inlet, the air passage having a feed opening through its wall, a float chamber connected with the feed opening, the air passage having a lower open end, the lower portion of the air pas- 130

- sage being of larger bore to form a shoulder below said feed opening, a spray plate having diverging sides arranged in the air passage with its sides abutting said shoulder, 5 the spray plate being perforated, and a cap for closing the lower open end of the air passage and engaging the spray plate to hold it in position, substantially as described.
- 10 5. In a carbureter, the combination of a vertical air passage, the air passage having a feed opening through its wall, a spray plate arranged in the air passage below the feed opening, the wall of the air passage 15 having a vertical opening communicating with the feed opening, the vertical opening being open at its lower end, a plug nozzle removably threaded into the open end of the vertical opening, the plug nozzle being 20 below and having a tapering outlet, the plug nozzle having a lateral opening leading to its hollow center, and a float chamber connected with the lateral opening of the plug nozzle, substantially as described.
- 25 6. In a carbureter, the combination of a vertical air passage, the air passage having a vertical opening in its wall, the wall of the air passage having a main feed opening extending therethrough from the vertical 30 opening, a spray plate arranged in the air passage below the main feed opening, the spray plate being perforated, a float chamber connected with said vertical opening
- below the main feed opening, the wall of the air passage having an auxiliary feed opening extending therethrough from said vertical opening, and a valve for controlling the flow from the auxiliary feed opening, substantially as described. 35
7. In a carbureter, the combination of a vertical air passage, the air passage having a vertical opening in its wall, the wall of the air passage having a main feed opening extending therethrough from the vertical opening, a spray plate arranged in the air 40 passage below the main feed opening, the spray plate being perforated, a float chamber connected with said vertical opening below the main feed opening, the wall of the air passage having an auxiliary feed opening extending therethrough from said vertical opening, a valve operative from the outside for controlling the flow from the auxiliary opening, a throttle valve in the air passage adapted when closed to partially close the auxiliary feed opening, and a butterfly valve for controlling the inlet of the air passage, substantially as described. 45
- 50 In testimony whereof I affix my signature 55 in presence of two witnesses.
